UNITED STATES PATENT OFFICE.

WILLIAM BOOTH, OF EAST LIVERPOOL, OHIO.

TELEPHONE-MOUTHPIECE.

1,240,659.

Specification of Letters Patent. Patented Sept. 18, 1917.

Application filed September 12, 1916. Serial No. 119,744.

To all whom it may concern:

Be it known that I, WILLIAM BOOTH, a citizen of the United States, residing at East Liverpool, in the county of Columbiana and 5 State of Ohio, have invented certain new and useful Improvements in Telephone-Mouthpieces, of which the following is a specification.

This invention relates to an improved telephone mouthpiece and has as its primary 10 object to provide a device of this character which may be readily connected to substantially any conventional type of telephone and of such construction that the mouthpiece will provide a sanitary attachment for 15 the telephone tending to minimize the possibility of infection therefrom.

The invention has as a further object to provide a mouthpiece formed to focus the 20 sound waves therein to be delivered to the telephone transmitter with a corresponding resultant increase in the clearness in the reproduction of the said waves.

And the invention has as a still further 25 object to provide a mouthpiece having a sound post through which the sound waves are transmitted and formed at its inner extremity to distribute said waves to the diaphragm of the receiver with a consequent 30 increased action of the said waves upon the said diaphragm whereby the efficiency of the telephone will be correspondingly increased.

Other and incidental objects will appear 35 as the description proceeds and in the drawings wherein I have illustrated the preferred embodiment of the invention and wherein similar reference characters designate corresponding parts throughout the several views:

Figure 1 is a perspective view showing my 40 improved mouthpiece applied to a conventional type of telephone, the telephone being partly broken away,

Fig. 2 is a sectional view more particularly showing the manner in which the 45 mouthpiece is connected to the telephone transmitter,

Fig. 3 is a sectional view of the mouthpiece particularly showing the construction 50 of the sound post thereof and the attaching ring which is arranged to surround the said post and adapted for connection to the telephone transmitter, and

Fig. 4 is a bottom plan view of the device. In order that the construction, operation

and mounting of my invention may be entirely clear, I have in the drawing illustrated the device in connection with a conventional type of telephone having a transmitter 10 closed by a cap plate 11 and carrying the usual diaphragm 12.

Coming now more particularly to the subject of the present invention, the mouthpiece is formed with an annular body 13 terminating at its inner extremity in an outwardly flared or bell-shaped flange or rim 14. Extending inwardly from the body 13 toward the free edge of the rim 14 is a substantially bell-shaped bowl 15 having its larger end presented outwardly to receive the sound waves. Formed on the inner side of the 70 bowl, at its smaller end, is a laterally projecting cylindrical sound post 16 surrounded by an annular channel 17, the outer wall of which is screw threaded as shown at 18. The body 13, the bowl 15, and post 16 are, 75 as illustrated in the drawings, integrally formed preferably from porcelain or other similar material.

Seated in the channel 17 is an annular attaching ring or member 19 which loosely 80 surrounds the post 16 and is externally screw threaded to engage the threads 18 upon the bowl 15. The ring 19 is preferably formed of metal; and filling the space between the said ring and the post 16 is a 85 suitable plastic filler 20 forming, as particularly shown in Fig. 2 of the drawings, a rigid connection between the ring and the said post, this filler also serving to lock the ring upon the bowl and support the said 90 ring with respect to the outer threaded wall of the channel 17 so that this wall and the said post will coact to receive any strain upon the ring. Consequently, any tendency of the ring to break the bowl and post 16, 95 under such strain, will be reduced to a minimum.

The post 16, at its inner extremity, is formed with a concave sound diffusing face or terminal 21 and leading through the said 100 post from the interior of the bowl 15 at its smaller end are a plurality of longitudinally inclined sound channels 22 which converge at their inner extremities toward the axis of the post or toward the center of the said 105 sound diffusing face of the post.

The attaching ring 19 is formed to engage within the usual mouthpiece opening in the

cap plate 11 of the transmitter 10 for connecting the mouthpiece with the transmitter as illustrated in Fig. 2 of the drawings, and it will now be observed that the rim 14 is of 5 a diameter substantially equal to that of the transmitter to overlie the said cap. The inner face of the bowl 15 is glazed or otherwise formed with a smooth surface so that sound waves directed into the said bowl will 10 be collected thereby and directed through the channels 22 to emerge centrally of the sound diffusing face 21 of the post 16. This concave face will then act to diffuse the said sound waves to strike against the area of 15 the diaphragm 12 of the transmitter. All of the sound waves coming within the bowl 15 will thus be collected to be transmitted to the diaphragm 12 with a correspondingly resultant increased action upon the part of 20 the said transmitter in reproducing the said waves. Moreover, the converging channels 22 will act to further center the said sound waves to be delivered into the concave face 21 of the post 16 in such a manner that the 25 said face will act to diffuse the said waves equally in all directions to the diaphragm 12 and thus cause an increased action of the sound waves upon the said diaphragm with a resultant clearness in the reproduction of 30 the sound waves thereby. I thus provide a particularly efficient construction for the purpose set forth and by forming the body of the mouthpiece of porcelain, the said mouthpiece may easily be cleaned while, at 35 the same time, the smooth surface thereof will tend to prevent the collection of germs upon the mouthpiece and consequently, the mouthpiece will thus provide a sanitary attachment for the telephone tending to minimize the possibility of infection therefrom.

Mounted upon the attaching ring 19 to extend radially therefrom beneath the rim 14 of the mouthpiece is a tag 23. This tag may be formed of celluloid or other suitable 45 material and at its inner extremity is provided with a suitable opening to receive the ring 19 with the outer extremity of the said tag preferably widened and extended beyond the periphery of the mouthpiece to receive the number of the telephone or other suitable indicia. By screwing the ring 19 in the cap 11 of the transmitter, the tag 23 may be tightly clamped between the said cap 50 and the rim 14 of the mouthpiece for securely holding the said tag in position, and it will be noted that I thus provide an arrangement wherein the use of any metal parts about the mouthpiece in such position 55 that the breath of the user of the telephone

would come in contact therewith, is eliminated so that the sanitary feature of the device is thus accordingly enhanced.

Having thus described my invention, what I claim and desire to secure by Letters Patent is:

1. A telephone mouthpiece including a body provided with a sound receiving bowl, a sound post projecting from the inner extremity of the bowl, the bowl being formed with a channel to surround the said post 70 and there being a sound receiving channel formed through the said post to communicate with the bowl, an attaching member for the mouthpiece carried thereby and seated in said first mentioned channel to surround 75 the said post, and a filler between the said member and the post.

2. A telephone mouthpiece including a body provided with a sound receiving bowl, a sound post arranged at the inner end of 80 said bowl and provided at its outer extremity with a concave sound diffusing face, there being a plurality of sound receiving channels formed through the said post to communicate with the bowl with the said 85 channels converging at their outer extremities towards the axis of the post to emerge through the central portion of the said sound diffusing face, and an attaching member for the mouthpiece carried by the said 90 bowl.

3. A telephone mouthpiece including a body provided with a sound receiving bowl, a sound post projecting from the inner extremity of the bowl, the bowl being formed 95 with a channel to surround the said post and there being a sound receiving channel formed through the said post to communicate with the bowl, an attaching member for the mouthpiece carried thereby and seated in 100 said first mentioned channel to surround the post, and locking means connecting the said member with the bowl and interposed between the member and said post.

4. A telephone mouthpiece including a 105 body provided with a sound receiving bowl, a sound post projecting from the inner extremity of the bowl, the bowl being formed with a channel to surround the said post and there being a sound receiving channel 110 formed through the said post to communicate with the bowl, an attaching member for the mouthpiece carried thereby and seated in said first mentioned channel, and means interposed between the said member and the 115 post for reinforcing the post.

In testimony whereof I affix my signature.
WILLIAM BOOTH. [I. S.]
